UNITED STATES PATENT OFFICE.

JAMES M. CURRELL, OF PASO ROBLES, CALIFORNIA.

WELL-DRILL.

1,065,298.

Specification of Letters Patent. Patented June 17, 1913.

Application filed August 28, 1912. Serial No. 717,604.

To all whom it may concern:

Be it known that I, JAMES M. CURRELL, a citizen of the United States, residing at Paso Robles, in the county of San Luis Obispo and State of California, have invented new and useful Improvements in Well-Drills, of which the following is a specification.

This invention provides a novel drill for 10 boring Artesian and oil wells, such drill being automatic in operation and actuated by means of hydraulic pressure after the principle of the hydraulic ram.

The invention supplies a drill of the character stated which will bore an opening of such a size as to admit of the casing following the drill, thereby overcoming the necessity of enlarging or ramming the bore in order to receive the casing.

20 The invention consists of the novel features, details of construction and combination of parts, which hereinafter will be more particularly set forth, illustrated in the accompanying drawing, and pointed out in 25 the appended claims.

Referring to the drawing, forming a part of the specification, Figure 1 is a vertical central section of a well drill embodying the invention, showing the relation of the parts 30 when the movable part carrying the bits is elevated. Fig. 2 is a view similar to Fig. 1, showing the relation of the parts when the bit-carrying member is lowered. Fig. 3 is a detail view, showing the bits moved 35 downward and inward so as to pass through the casing when it is required to lower the drill into position. Fig. 4 is a horizontal section on the line $x-x$ of Fig. 1. Fig. 5 is a horizontal section on the line $y-y$ of 40 Fig. 1.

Corresponding and like parts are referred to in the following description, and indicated in all the views of the drawing, by the same reference characters.

45 The body of the drill comprises two sections 2 and 12, which are connected by means of a screwthread joint 4, both sections being hollow so as to receive the working parts. The upper section 2 has an inner shoulder 50 21 near its upper end against which abuts an expansible helical spring 1, the lower end of such spring engaging an outer shoulder α of a tubular member 3, slidably mounted within the body and normally held pressed 55 downward by means of the spring 1, which is located within the section 2. The upper

end of the section 12 forms a stop to engage the annular enlargement of the tubular member 3 to limit the relative downward movement of such member. Openings 6 are 60 formed in the sides of the section 12 near the joint 4 between the two sections 2 and 12. Other openings 7 are formed in the sides of the tubular member 3 near its lower end. When the body of the drill is moved 65 downward, as indicated in Fig. 2, the openings 6 and 7 are caused to register, thereby providing an escape for the water. Other openings 13 are formed in the sides of the section 12 some distance below the openings 6. These openings 13 provide for an outrush of the water to enable the same to attain a proper momentum when the outflow is suddenly cut off by means of a valve 10, the reaction forcing the body of the 75 valve downward and bringing the cutting bit in forcible contact with the work. Above the openings 13 is formed a valve seat 11, which is renewable and receives the valve 10, which has a limited movement within the 80 section 12, being held unseated by means of a spring 8, which is of the helical contractile type, the upper end of the spring being attached to a pin 9 supported in openings 85 in the sides of the section 12.

The bits 20, two in number, are of similar formation and are mounted so as to have both a longitudinal and a lateral movement imparted thereto, whereby provision is had for moving the bits inward at their cutting 90 ends to admit of passing the drill through the casing when introducing the drill into the well or bore. The bits 20 are mounted upon the ends of a cross bar 16, which has a limited movement in the lower portion of 95 the body, the latter being reduced, as indicated at b , and said reduced portion having longitudinal slots c in which the cross bar 16 has a limited vertical play. The shoulders formed at the base of the reduced part b 100 are inclined, as indicated at e , and the upper ends of the bits are correspondingly inclined so as to engage under the inclined or under cut shoulders e and thereby hold the bits in proper position when the drill is in operation. The openings f formed in the upper 105 ends of the bits 20 are elongated vertically to admit of the lower or cutting ends of the bits having a lateral movement whereby said bits may be contracted, as indicated in Fig. 3, or expanded, as indicated in Figs. 1 and 2. The lower ends of the bits are widened,

as indicated at *g*, to engage under the reduced portion *c* of the body. The shanks of the bits are placed against the sides of the reduced portion *c* and their inner upper portions are cutaway at a slight inclination, as indicated at *h*, terminating in shoulders *i*, which latter are located some distance above the lower end of the reduced part *c* when the bits are in working position, as indicated in Figs. 1 and 2. When it is required to contract the bits to enable the drill to pass through the casing the bits are moved downward until the shoulders *i* clear the lower end of the reduced part *c*, when said bits may be pressed inward, as indicated in Fig. 3, thereby enabling the drill to be inserted within a casing and passed therethrough. A rod 15 or like part is mounted in the lower portion of the body and its lower end has an opening to receive the cross bar 16. A spring 25 is mounted upon the rod 15 and is confined between a nut at the upper end of the rod and an inner shoulder 26 near the lower end of the body. The spring 25 is of the expandable helical type and normally exerts a pressure upwardly upon the rod 15 to hold the bits 20 in working position, as indicated in Figs. 1 and 2. The bits have shoulders 27 near the upper ends of their shanks to engage the lower end of the casing to force the bits downward preliminary to withdrawing the drill from the well through the casing.

The tubular member 3 has a portion 28 which extends through the upper end of the hollow body and to which the tubing is coupled for supplying water under pressure to the drill. The extension 28 has a feather and spline connection with the hollow body to enable both to turn in the operation of the drill to bring the cutting edges of the bits in new positions, as the work progresses. When it is required to pass the drill through the casing the bits are moved downward and after the shoulders *i* have cleared the lower end of the reduced part *c* of the body the bits are pressed inward, as indicated in Fig. 3, thereby enabling the drill to be inserted into and passed through the casing. After the bits have cleared the lower end of the casing a slight jar suffices to disengage the shoulders *i* from the lower end of the part *c* when the bits are drawn upward into working position by means of the spring 25. Water under pressure is supplied to the tubing or line of pipe connecting the tubular member 3 with the source of water supply. The valve 10 is held unseated by the spring 8 until the water has acquired a sufficient momentum when the valve 10 will close by the combined weight and momentum of the water, thereby producing a reaction similar to the hydraulic ram, which exerting a force upon the hollow body carries the same downward and brings the bits in forcible contact

with the work. When the force of the blow has been delivered the openings 6 in the sides of the hollow body register with the openings 7 of the tubular member, thereby providing an outlet for the water and the pressure being thus diminished the spring 8 comes into play to unseat the valve 10, when the water will pass through the tubular member and outwardly through the openings 13 of the hollow body, thereby further reducing the pressure when the spring 1 will come into play to return the hollow body to normal position, thereby throwing the openings 6 and 7 out of register. The water under pressure will continue to flow downwardly through the tubular member and outwardly through the openings 13 until it has acquired a momentum sufficient to seat the valve 10, when the resultant reaction will again force the body downwardly and cause the bits to deliver an effective blow. This operation will be repeated and is automatic. The water escaping from the drill after performing work is utilized to carry off the cuttings, sand and the like resulting from boring the well, thereby preventing binding of the drill and casing so that both may be properly advanced to the work.

When it is required to remove the drill from the well it is necessary only to draw upwardly upon the line of pipe or tubing connected with the member 3, thereby bringing the shoulders 27 of the bits in contact with the lower end of the casing, when the bits will be moved downwardly and at the same time pressed inwardly to cause the shoulders *i* to engage under the lower end of the reduced part *c*, thereby permitting withdrawal of the drill through the casing in the manner stated.

From the foregoing description, taken in connection with the accompanying drawing, the advantages of the construction and of the method of operation will be readily apparent to those skilled in the art to which the invention appertains, and while I have described the principle of operation of the invention, together with the device which I now consider to be the best embodiment thereof, I desire to have it understood that the device shown is merely illustrative, and that such changes may be made when desired as are within the scope of the claims appended hereto.

Having thus described the invention what is claimed as new, is:

1. In a hydraulic drill the combination of a member having an opening therethrough and a lateral discharge, a body slidably mounted upon the said member and having upper and lower outlets, said body adapted to receive a tool, means for yieldingly pressing the said body upwardly upon the said member to throw the upper outlet out of register with the lateral discharge of the

said member, and a valve carried by the said body and arranged between the lower outlet thereof and the lower end of the said tubular member.

5 2. In a hydraulic tool the combination of a member having an opening therethrough and a lateral discharge leading from said opening, a hollow body slidably mounted upon the said member and having relative 10 upper and lower outlets, means for limiting the movements of the body upon the member, a helical expansible spring interposed between the member and body to hold the latter relatively elevated, and a valve 15 arranged within the hollow body below the before mentioned member and above the lower outlet of the body and normally held unseated and adapted to close when the momentum of the water passing through the 20 said member has acquired a pressure sufficient to seat the valve to press the body downwardly.

3. In a hydraulic tool of the character set forth, the combination of a tubular member 25 having an outer shoulder and formed with a lateral opening, a hollow body slidably mounted upon the tubular member and having upper and lower lateral outlets and an intermediate valve seat, an expansible heli-

cal spring located within the body and confined between an inner shoulder thereof and the shoulder of the tubular member to normally hold the body relatively elevated, a valve arranged within the body to close downwardly upon the said valve seat, and a 35 spring for normally holding said valve unseated.

4. In a hydraulic tool of the character set forth, the combination of a tubular member having an outer shoulder and a lateral opening, a hollow body comprising two sections connected by a screwthread joint slidably mounted upon said tubular member, an expansible helical spring arranged within the upper section of the hollow body and confined between the shoulder of the tubular member, and an inner shoulder of the body, the lower section of the latter having upper 45 and lower lateral openings and an intermediate valve seat, a valve for closing downwardly upon said valve seat, and a spring for normally holding the valve unseated.

In testimony whereof I affix my signature in presence of two witnesses.

JAMES M. CURRELL.
